CLAMP

Nathan Rodney Schwartz, New York, N. Y.

Application September 30, 1947, Serial No. 776,891

3 Claims. (Cl. 248—226)

1

This invention relates broadly to lamps such as work lamps, desk lamps and others adapted to be placed upon a horizontal surface, and more particularly to means mounted upon the underside of such lamps, whereby they may be rigidly and removably retained upon vertical surfaces, rendering such lamps universally useable.

It is a further aim of the present invention to provide a work lamp with clamp means, whereby such lamp may be secured to a bed frame, bed post, pipe, table edge, and any other desirable surface, whether vertical or angular.

And it is yet another purpose of the present invention to provide a clamp by means of which an object on which it is secured, may be removably secured to a vertical, horizontal or angular support.

And still another advantage of the present invention resides in the provision of a clamp for attachment to a lamp or any other desirable object, whereby the object may be rigidly and securely attached to a rectangular support, such as a bed frame, or a circular support such as a pipe.

And yet another feature of the present invention resides in the provision of clamp means for lamps and other objects, whereby the said objects may be removably secured to vertical or angular surfaces without the use of screws, bolts or other tightening means.

These and other meritorious objects and advantages, which will become more fully apparent as the description hereof proceeds, are attained by the novel construction, combination and arrangement of few and simple parts, hereinafter described, and illustrated in the accompanying drawing, forming a material component of this disclosure, and in which:

Figure 1 is a top plan view of a desk lamp, the underside of which is provided with a clamp made in accordance with the present invention.

Figure 2 is a side elevational view of the lamp illustrated in Figure 1.

Figure 3 is a bottom plan view of the lamp, showing the clamp in an inoperative position.

Figure 4 is a side elevational view, partly in section, of the lamp, the section being taken on line 4—4 of Figure 1, and

Figure 5 is a side elevational view, similar to Figure 4, but showing the clamp in operative position about a tubular support.

Referring in greater detail to the drawing, the numeral 10 designates in general a lamp, such as a desk lamp, work lamp, etc., having a base 11, here illustrated as having the shape of a flat-iron, one end of which is relatively broad, whereas the

2

other end is pointed. Near the broad end, a socket 12 is provided, preferably mounted in a swivel member 13. An appropriate opening may be provided near the rear of the base 11 for the electrical cable 14 therethrough, which cable may thence pass through the central opening in the roof of base 11 into the socket 12 in the conventional manner and for the usual purpose. None of these elements are new, hence they do not form part of this invention.

It has heretofore been mentioned that base 11, at substantially its highest point, is provided with an opening which, for the purpose of this particular embodiment is circular in cross-section, but which obviously may be of any desired shape. The neck of swivel member 13 extends through this opening upwardly, and the end of the said neck is secured to the inner surface of the roof of base 11 by eyelet 15. Eyelet 15 also secures 15 to the underside of the roof of base 11 a pair of brackets 16 and 17, the said brackets being arranged cross-wise as is illustrated in the drawing, arm 16 extending throughout the width of base 11 and arm 17 extending lengthwise, as Figure 3 clearly shows. The said arms are curved to conform substantially with the contour of the interior of the base 11, and the ends of the brackets may be provided with rubber tips 18 projecting from base line 19, so that the device may rest 20 upon these tips when it is placed upon a desk, table or the like surface. Each end of arm or bracket 16 is provided with an opening, in which is swingingly retained one end of an arm 20. At its center, arm 20 is curved to form off-set 22.

The invention further comprises another arm 23, the ends of which embrace arm 20 at points near offset 22, so that a swinging arrangement is achieved for arm 23. This arm is also provided with an offset, referred to by the numeral 24, and a pair of springs 25, secured between arms 20 and 23, have for their purpose to normally press both arms against the front portion of bracket 16. For the purpose of illustration, Figure 5 shows the device secured to a cylindrical support 26 and the device is provided with an incandescent lamp bulb 27.

The operation of the device is very simple and highly effective. When it is desired to place the lamp upon a table, desk or such support, it will 50 come to rest upon tips 18. These tips have rubber covering, in order that the surface of the support may not be marred. It is not necessary of course, to cause these tips to extend beyond base line 19, in which the device will rest upon 55 the edge of base 11. When it is desired to secure

the device to another support, such as the cylindrical support 26 shown in Figure 5, arm 23 is swung backward against the pressure of springs 25 and thence pulled upwardly and forwardly, and released about the support which it is intended to grip. There the device will be held rigidly and securely. The support may be of any shape and any diameter. Arm 23 may have a rubber covering so that the surface of the support may not be marred.

While for purposes of illustration, a lamp has been referred to in this disclosure, it is clear that the clamp arrangement may be used with equal effectiveness in connection with other devices. It is to be clearly understood that the above disclosure is intended to be illustrative and descriptive only of the best known embodiment of the invention, and not as limitative or restrictive to the exact details shown, applicant reserving the right to make such changes in the construction or application of the device as may come within the scope of the appended claims, without thereby departing either from the spirit or the scope of the invention.

Having thus described the invention, what is claimed as new and desired to secure by Letters Patent, is:

1. A clamp securable to the roof of a foot member, said clamp comprising a pair of brackets, said brackets positioned rectangularly in relation 30

to each other, each end of said brackets terminating in a raised tip, a rocking arm, said rocking arm anchored at its ends in a pair of opposed tips, said rocking arm provided with an offset, a second rocking arm, said second rocking arm secured to said first rocking arm, and means normally urging said second rocking arm against the other of said brackets.

2. A clamp comprising a pair of cross-wise positioned brackets, the ends of each of said brackets terminating in a raised tip, a rocking arm, said rocking arm anchored at its ends in the raised tips of one of said brackets, a second rocking arm secured to said first rocking arm, said second rocking arm provided with an offset, and spring means normally urging said second rocking arm against the other of said brackets.

3. A clamp comprising a pair of cross-wise disposed brackets, said brackets joined at their center, each end of said brackets terminating in a raised tip, a spring, said spring curved to form a rocking arm, said spring anchored at its ends at the opposed tips of one of said brackets, said spring forming an offset at its center, a second spring curved to form a second rocking arm, and spring means joining said first rocking arm and said second rocking arm, normally urging them against the other of said brackets.
